UNITED STATES PATENT OFFICE.

WARREN F. FRASER, OF WESTBORO, MASSACHUSETTS.

LAPPING MACHINE AND METHOD OF TRUING THE LAPPING ELEMENTS.

Application filed October 8, 1924. Serial No. 742,477.

This invention relates to abrading machines and more particularly to a lapping machine of the type shown in my copending application Serial No. 684,547 filed January 5, 1924, as well as to a method of truing the lapping elements.

A lapping machine of this type is one in which the work is ground between oppositely disposed laps mounted for movement towards one another. The work is moved in a suitable holder located between the laps which is given a compound motion along a continuously changing path, the parts being so arranged and the work so moved that every portion of the lapping surface is covered by the work at some time during its movement, whereby the formation of lines on the work is prevented and a uniform wear of the lapping elements insured.

In machines of this type the active surfaces of the laps must approximate a geometrical accuracy, since the shape of the laps determines the shape of the work. It is, therefore, necessary to true the surfaces of the laps periodically in order to insure the formation of correctly sized work. In machines of this type, as heretofore constructed, it has been necessary to remove the laps from the machine and to bring them down to the required surface in a lathe or other suitable machine, after which the laps must be remounted in the lapping machine in proper positions for the lapping operation. This procedure has involved various difficulties, in addition to being expensive in consumption of time and the use of other machines for truing the laps.

It is the prime purpose of my invention to provide a construction which will permit the laps to be trued without removal from the machine; and

It is a further object of this invention to provide a novel method of truing the laps in situ, which will insure the provision of an accurate surface with the minimum of attention and skill on the part of the operator of the machine.

With these and further objects in view as will be apparent in the following disclosure, my invention resides in the combination of parts and in the steps of a process as set forth in the specification and covered by the claims appended hereto.

Referring to the drawings which illustrate one embodiment of my invention:

Figure 1 is a vertical elevation with parts

shown in dotted outline of a simplified type of apparatus;

Fig. 2 is a detailed view on the line 2—2 of Fig. 1; 60

Fig. 3 is a detail elevation of the parts shown in Fig. 2 and;

Figs. 4, 5 and 6 are diagrammatic representations of the relative positions of laps and truing elements during successive stages 65 of my method.

Fig. 7 is a partial plan view of one form of work holder mounted on its carrier; and

Fig. 8 is a perspective view partly in section of the work holder carrier. 70

Referring to the drawings, I have there shown a machine base 10 on which are mounted the two annular lapping elements 11 and 12, between which the work is to be abraded. While these elements may be otherwise mounted for carrying out the process herein described, I have shown the upper lapping element 11 vertically movable towards and from the lower lap. The lower lap 12 is positioned on an annular member 14 which in turn is suitably mounted on three supporting projections 15 fixed to the base 10 of the machine, the mounting of these elements being rigid and such that the lower lap 12 is held securely in position without danger of vibration or other detrimental movement. 75

The upper vertically movable lap is preferably carried by a post 18 slidably mounted in two bearings 19 and 20 which are suitably constructed and mounted on the frame 21 which projects upwardly from the base to a position over the lapping elements. While this post may be vertically moved by suitable operation mechanism I have shown it in simplified form in the present case as manually movable. For this purpose the post is provided with a slot 22 near its upper portion within which rides a pin 23 projecting inwardly through the bearing 20, 100 thus permitting vertical movement but preventing turning of the post.

In order to permit accurate alignment of the faces of the two laps, I mount the upper lap on a universal joint which comprises a ball 25 pinned to the lower end of the post 18 to which is adjustably clamped the two rings 26 and 27 forming the socket of the joint. The lower ring 27 is fastened to the upper one by suitable bolts 28, and carries 105 outwardly projecting arms 29 to which is bolted the carrier of the lap or the lap it-

self. In the present case I have shown an annular ring 30 constituting this carrier bolted to the arm 29.

Each of the laps 11 and 12 may be made of suitable material as is well known in this art, and may be either a stone of suitably bonded abrasive grains such as is employed for grinding wheels or it may be made of metal, such as iron. In the latter case, a loose abrasive material mixed with water or oil is employed to furnish the abrading action. As illustrated, the laps are made of vitrified bonded abrasive grains of the grinding wheel type and may accordingly be secured to their supports by suitable means such as a cement, sulfur, or the like.

In accordance with one phase of my invention, I propose to true the adjacent, opposed faces of the laps by means of an abrading element 31 placed therebetween and suitably moved to grind the faces of the laps until they lie in parallel planes. This truing element may be made of abrasive material similar to thelapping elements or it may be of metal and used with an abrasive powder or compound for the abrading operation. I prefer to move the truing element between the laps through a path which does not repeat itself for many cycles, and thereby prevent the formation of ring markings.

One problem involved in truing the laps lies in the fact that the intermediate truing element may not have faces which are exactly parallel with the desired planes of the laps. As illustrated in an exaggerated fashion, in Fig. 4, this truing element may be somewhat conical in shape and so tend to form the laps with tapered faces. In accordance with my invention, I propose to use such a truing element without providing it with accurately shaped faces and to carry out the method in such a manner that any error is automatically rectified. I accordingly abrade thelapping faces with such crudely formed truing element until the laps and the truing element have attained a uniformity of surface and the adjacent surfaces of each lap and the truing element are substantially parallel. Thereafter I remove the truing element from the machine and turn it bottom side up and again resume the truing operation. As shown in exaggerated form in Fig. 5, the truing element will be largely out of contact with the laps but after moving the truing element through its grinding cycle for a time, it will be found that the truing element and the laps have worn each other away and the laps have now approached a more nearly perfect condition. By reversing the truing element one or more times thereafter, I may bring the laps finally to a condition in which the lap surfaces are substantially parallel planes.

In order to give the truing elements a suitable motion for carrying out my method, I may employ the construction illustrated in my copending application or as shown herein in simplified form. As illustrated, 70 I provide a shaft 32 suitably mounted in bearings on the machine which is rotated by a pulley 33 or other proper driving mechanism. A sleeve 34 surrounding the shaft 32 is also mounted for rotation thereabout, the upper end of this sleeve carrying a collar 35 which bears against the central hub of the base plate 36 of the machine. The sleeve may be suitably rotated, as by means of a pulley 37 fixed to its lower end. 80 These two rotative elements furnish a compound movement through a carrier for the grinding element placed between the laps. This carrier is removably located between the laps and may comprise a suitable support for the work being ground as well as for a truing element.

In order to give the work or the truing element the desired compound rotary movement, I form the shaft 32 with an enlarged head 40 having an exterior cylindrical surface eccentric with the shaft. A split collar 41 is clamped on this cylindrical head and may be suitably adjusted in position by loosening a clamp screw and revolving the collar about its center. A driving pin 43 is mounted in a socket in the collar with its axis eccentric to the center of the head 40. This head is also so positioned that as the collar 41 is adjusted about the head 40, the pin may be brought into axial alignment with the shaft 32 or by revolving it further around the center of the head, it may be given the maximum eccentricity as shown in the drawing. By means of this adjustment, 100 I may vary the throw or radius of movement of the pin 43.

It will therefore be seen that rotation of the shaft 32 gives the pin 32 a movement of revolution which may be transmitted to the work holder by a suitable connection. The holder for the truing element comprises a plate shaped carrier 44 to which the abrading ring 31 is clamped by a clamping ring 45. This carrier is provided with a centrally located hub adapted to fit over a yoke member 46 which is likewise rotatably mounted over the pin 43. As will presently be explained, this yoke member 46 which is given the compound movement is left normally in place when the work or the truing element is removed and it is merely necessary to drop the work carrier or the plate 44 over this yoke member in proper position to permit thelapping and truing operations.

It will be seen, so far as now described, that rotation of the pin 43 will carry the center of the truing element about a circle of small radius. In order to give this holder 44 a rotary motion about its center as it re-

volves, I provide a connection between the plate 44 and the sleeve 34 which is meant to rotate at a slower speed than the inner shaft 32. The collar has an outwardly projecting 60 which has an up-turned portion 51 provided with a hole therethrough. Connection is made between this arm 50 and the driving plate 44 through a separate member comprising a horizontal plate 52 which has a pin 53 projecting upwardly at one end and another pin 54 projecting downwardly at its opposite end. The pin 54 fits rotatably within the hole in the portion 51 of the crank arm and the pin 53 is likewise 15 adapted to be pivotally mounted in a hole 55 in the upwardly projecting pin 56 of the driving yoke 46 which in turn fits within a hub in the place 44. Cover plates 57 over the upper ends of the holes in the hub of 20 the yoke 46 prevent admission of abrasive to the bearing pins 43 and 53.

It will therefore be seen that when the shaft 32 and the sleeve 34 are rotated at different speeds, the first rapidly and the second slowly, the plate 44 and consequently the truing element 31 will be rotated slowly about its center while the center is revolved at a rapid rate. These two movements cause the truing element to be carried around in 25 a rapid loop-like motion while it travels about the axis of its driving shaft. These motions are so timed and related that the abrading or truing element and the laps are moved relatively in a compound nonrepeating path; that is a given spot on the truing element does not travel in the same path on a lap until it has been revolved many times. This insures even wear of the laps. It, however, will be understood that the 30 driving mechanism may be suitably constructed to give any desired movement so far as the broader aspects of my invention are concerned. It will also be understood that by adjusting the pin 40 in its collar 41, 35 I thereby vary the extent of the loop-like motion of the truing element relative to the laps. If the pin 43 is axially aligned with the shaft 32, the element 31 will then be given a simple movement of revolution about 40 the center line of the laps. Also, it will be understood that it is feasible within the broader aspects of my invention to move the laps instead of the central abrading element to true the laps, it being merely necessary 45 to provide a relative movement therebetween.

It will be understood that the abrading element is employed only when necessary to true the lap faces. During the normal operation of the machine, the abrading element is replaced by a work holder. The carrier for the work holder fits over the driving pins 43 and 53 and is arranged to move the work through the same path as that given 50 to the abrading element. The work carrier

as shown in Figs. 7 and 8 may comprise a plate 60 having an annular flange 61 arranged to hold the removable disk shaped work support 62 in position. The latter may rest on the plate 60 and be keyed there- 60 to by keys 64 so that the parts will revolve together. The carrier 60 has a boss 65 projecting therefrom which is provided with openings into which the pins 43 and 53 project, these being so arranged that pin 53 is 70 concentric with the carrier and pin 43 eccentric relative thereto. The work holder 62 which is thinner than the distance between the laps may be provided with holes 66 of suitable shape to fit the work pieces 75 to be treated.

The operation of the device and of my method will be apparent in view of the above explanation, and it will also be obvious that various modifications may be made 80 therein within the scope of the appended claims.

Having thus described my invention, what I claim as new and desire to secure by Letters Patent is:

1. The method of truing two opposed lap faces to bring them into parallel planes comprising the steps of relatively moving an abrasive element of wearable material having extensive plane surfaces between and in 90 contact with said lap faces to abrade the same, reversing said element and repeating the abrading operation upon the laps with said element in its reversed position.

2. The method of truing the two opposed surfaces of flat laps to bring them into parallel planes comprising the steps of moving an abrading element of wearable abrasive material, which has a plane face contacting with each of the laps, in a compound nonrepeating path relative to the laps so as to abrade them, reversing said element so that each lap surface will be acted upon by that face of the abrading element which formerly contacted with the other lap, again abrading 100 the laps thereby, and repeating the cycle of abrading and reversal until the surfaces of the laps are parallel and true planes to a high degree of accuracy.

3. The method of truing the opposed surfaces of flat lapping or abrading elements to bring them into highly accurate parallel planes comprising the steps of introducing a third element, having extensive plane faces, between said lap faces and causing a 115 relative lapping movement between them whereby the face of each lap and the contacting faces of said third element, are each abraded until they have extensive surfaces in contact, reversing the third element and 120 repeating the lapping movements until the said surfaces are again in extensive contact, and repeating said process until the desired degree of accuracy of plane and parallelism is obtained.

4. A device for truing the opposed faces of the lapping elements in a lapping machine having two laps with opposed disk faces and including mechanism to cause relative movement between the laps and work placed therebetween to lap said work, comprising a removable element having extensive plane faces which are capable of abrading said lap faces simultaneously and means whereby said element may be mounted between the said laps and moved by said mechanism to true the laps.
5. A device for truing the opposed faces of the lapping elements in a lapping machine having two laps with opposed disk faces, comprising a wearable abrading element having plane faces, means removably supporting said element with its faces between and in contact with the laps, and means to move said element and the laps relative to each other in a compound non-repeating motion to abrade the laps, said parts being so constructed and arranged that the laps may be repeatedly abraded, each first with one face of said element and then with the other, and their faces ultimately brought into parallelism.
6. A device for truing the opposed faces of the lapping elements in a lapping machine having two laps of abrasive material with substantially parallel opposed disk faces, and having means to mount and rotate a carrier therebetween in a compound non-repeating motion, comprising an abrading element of disk shape, means for removably mounting the abrading element on said carrier with its plane faces contacting with the two lap faces and so arranged that it may be reversed and means permitting the laps to bear against said element and be trued by the rotative movement of the carrier.

Signed at Worcester, Massachusetts, this 6th day of October, 1924.

WARREN F. FRASER.
